(57) **CLAIM**

The ornamental design for a light emitting digital display panel, as shown and described.

DESCRIPTION

FIG. 1 is a perspective view of a light emitting digital display panel showing the design, the perspective view showing a light emitting front face;

FIG. 2 is a front elevation view thereof;

FIG. 3 is a front elevation view thereof in which three portions are indicated for enlarged views shown in of FIG. 10, FIG. 17, and FIG. 24;

FIG. 4 is a back elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is an enlarged perspective view of the right side panel shown with the center and left side panels removed for ease of illustration;

FIG. 10 is a front elevation view of the right side panel as indicated by detail “10” in FIG. 3;

FIG. 11 is a back elevation view thereof;

FIG. 12 is a left elevation view thereof;

FIG. 13 is a right elevation view thereof;

FIG. 14 is a top plan view thereof;

FIG. 15 is a bottom plan view thereof;

FIG. 16 is an enlarged perspective view of the left side panel shown with the center and right side panels removed for ease of illustration;

(Continued)

FIG. 17 is a front elevation view of the left side panel as indicated by detail "17" in FIG. 3;
 FIG. 18 is a back elevation view thereof;
 FIG. 19 is a left elevation view thereof;
 FIG. 20 is a right elevation view thereof;
 FIG. 21 is a top plan view thereof;
 FIG. 22 is a bottom plan view thereof;
 FIG. 23 is an enlarged perspective view of the center panel shown with the left and right side panels removed for ease of illustration;
 FIG. 24 is a front elevation view of the center panel as indicated by detail "24" in FIG. 3;
 FIG. 25 is a back elevation view thereof;
 FIG. 26 is a left elevation view thereof;
 FIG. 27 is a right elevation view thereof;
 FIG. 28 is a top plan view thereof; and,
 FIG. 29 is a bottom plan view thereof.

The broken lines in FIG. 4, FIG. 11, FIG. 18, and FIG. 25 illustrate portions of the light emitting digital display panel form no part of the claimed design. The dash-dot broken lines in FIG. 3 indicate areas of the detailed views and form no part thereof.
